UNITED STATES PATENT OFFICE.

HERBERT J. BRAGDON, OF ALTON, ILLINOIS, ASSIGNOR TO THE CHICAGO STOPPER COMPANY, OF CHICAGO, ILLINOIS, A CORPORATION OF ILLINOIS.

RECEPTACLE STOPPER.

Application filed August 17, 1921. Serial No. 493,061.

To all whom it may concern:

Be it known that I, HERBERT J. BRAGDON, a citizen of the United States, and resident of Alton, county of Madison, and State of Illinois, have invented a certain new and useful Improvement in Receptacle Stoppers, of which the following is a full, clear, concise, and exact description, reference being had to the accompanying drawings, forming 10 a part of this specification.

My invention relates to an improved stopper for a bottle or other receptacle, the stopper being constructed of relatively inexpensive material; being adapted when 15 forced, or fitted, into the neck of a bottle, automatically to hold itself in fluid-tight engagement with the bottle neck; but nevertheless being capable of easy removal following a simple and natural operation which 20 releases the pressure of the stopper against the bottle neck.

As the broad plan and principle of my invention, as well as the details of the herein illustrated embodiment thereof, can best 25 be understood from a description read in connection with illustrative drawings, I shall proceed at once to a discussion of the accompanying drawings, in which:

Figure 1 is a side elevation of my stopper 30 as it appears prior to its insertion in the neck of a bottle;

Figure 2 is an axial sectional view of the stopper, this view likewise illustrating the stopper as it appears prior to insertion in 35 a bottle neck;

Figure 3 is a transverse section taken on line 3—3 of Figure 2;

Figure 4 is an axial sectional view of the stopper and a bottle neck in which the stopper 40 has been forced or inserted;

Figure 5 is a transverse section taken on line 5—5 of Figure 4;

Figure 6 is a view similar to Figure 5, but illustrating the stopper after it has been 45 "coiled" to relieve its pressure against the bottle neck;

Figure 7 is an elevational view illustrating a number of the elements of the stopper as they appear at an intermediate step 50 in the manufacture of the stopper;

Figure 8 is a bottom plan view of the parts shown in Figure 7;

Figure 9 is an isolated elevation of one 55 of two similar non-metallic strips used in the construction of the stopper;

Figure 10 is an isolated elevation of the metallic strip employed in the stopper construction;

Figure 11 is an elevation of the staple or winding post as it appears prior to its assembly with the stopper head;

Figure 12 is an axial sectional view of a modified stopper construction;

Figure 13 is a section taken on line 13—13 of Figure 12;

Figure 14 is a top plan view of the stopper shown in Figures 12 and 13; and

Figure 15 is an elevational view of a tool or key that may be employed to facilitate removal from a receptacle of a stopper of 70 the kind illustrated in Figures 12 to 14, both inclusive.

Figures 7 to 11, both inclusive, are drawn as closely as possible to the exact size of a commercially developed embodiment of 75 my invention. Figures 1 to 6, both inclusive, have been drawn on a larger scale.

The stopper illustrated in Figures 1 to 11, inclusive, comprises a head or disc A, a staple B, a pair of non-metallic strips 80 CC, a metallic strip D, a strip E of relatively thin paper, a relatively stiff but thin disc F, an impervious cup G and a relatively thin paper disc H.

The disc A is preferably formed of thick 85 cardboard capable of being pierced by the points of staple B, but may be constructed of any suitable material, such as wood, fibre, metal, etc. Staple B is preferably formed of wire and is conformed to provide the loop 16, shoulders 17—17 and the spaced apart and pointed extremities 18—18 (see Figure 11).

Each of the strips CC is formed of a material, such as comparatively heavy manila paper, which is fairly stiff, but has some 90 inherent resiliency and flexibility. One of the edges of each strip CC is notched intermediate the strip ends, as indicated at 19—19. Strip D is formed of any relatively thin sheet metal which has an inherent tendency to unwind when coiled. Strip D is of

substantially the same width but shorter than strips CC. A notch 20 is formed in one edge of strip D at a point intermediate 95 its ends. Strip E is conveniently of substantially the same width and length as strips CC and is formed of some comparatively cheap material such as thin manila paper.

Strip E is notched at 21. Disc F is preferably formed of some material that is im- 100 105 110

pervious to moisture, such as paraffined or waxed paper or cardboard, cork or the like. Cup G is formed of an impervious material, such as metal foil, paraffined or waxed paper or the like. In many cases I find it desirable to employ a two-ply cup, i. e., one ply of metal foil and the other of paraffined or plain paper. In such a cup the metal foil usually, but not necessarily, forms the outer layer. Disc H is formed of paper. It gives disc A a finished appearance and serves to receive any advertising or other printed matter that may be desired.

In constructing the stopper, the strips CC are placed side by side with the strip D between them, the notches 19—19 and 20 being brought into registry. Strip E is now, or has been previously, adhesively applied to one of the strips C and projects a substantial distance beyond one end thereof, notch 21 registering with notches 19—19 and 20. The several strips CC, D and E are now slipped through loop 16 of staple B, the lower portion of the loop being caused to engage in the several aligned notches. The cardboard disc A is now forced down upon the pointed ends 18—18 of B and the pointed ends are clinched as illustrated in Figures 2 and 4. When disc A is formed of heavy and comparatively soft cardboard, the clinched ends of the staple and the shoulders 17—17 may be caused to lie flush with, or even within, the upper and lower surfaces of disc A. The several strips are now wound or coiled around loop 16 in the manner most clearly illustrated in Figures 3, 5 and 6. The outermost convolution of the coil of strips consists of the thin paper E, the strip E being adhesively secured to itself to limit the coil of strips to a predetermined diameter or circumference. The coiled strips are now preferably placed in a shaping die which need not differ materially in shape from the neck of the receptacle with which the finished stopper is subsequently to be used. A die of this kind will give the coil of strips such taper as may be required for ordinary receptacles. Disc F is now placed against the bottom of the shaped coil of strips and the impervious cup G is positioned around the coil of strips as shown. The cup is preferably adhesively secured to the outermost convolution of the coil of strips, but this is by no means absolutely necessary. The cup is not secured to disc A, but the upper margin of the cup lies snugly in contact with such disc. The clinched extremities of staple B are now concealed by adhesively applying paper disc A, and the stopper is ready for use.

The stopper is preferably inserted into a bottle or other receptacle of the type indicated at X by direct pressure applied to the disc A, the pressure being applied in a line parallel to the axis of the bottle neck.

When so inserted the body portion of the stopper,—that is, that portion of the stopper which consists of the coil of strips and the cup,—is compressed by the wall of the receptacle. The nature of this compression will most clearly appear from a comparison of Figures 2 and 4 and a comparison of Figures 3 and 5. The dotted lines in Figures 4 and 5 indicate the normal outlines from which the stopper body is compressed by its insertion into the receptacle under pressure. The stopper body thus compressed forms a fluid-tight closure for the bottle neck. Experience has demonstrated that the compressed stopper body will withstand very considerable gaseous pressures within the receptacle and that it is practically impossible to withdraw a properly inserted stopper by a direct outward pull.

The stopper may be very easily removed simply by turning the disc A, and with it the staple B, in the direction opposite to that in which the strips were originally coiled around the winding loop. This turning of disc A and staple B causes the inner convolutions of the strips to be more tightly coiled around loop 16 and upon each other, and relieves, or greatly reduces, the pressure with which cup G bears against the wall of the receptacle. With the pressure of the stopper body against the receptacle relieved, the stopper may be easily removed by the hand with which the disc A was grasped and turned. It will be obvious that when the inner convolutions of the coiled strips are being more tightly coiled around loop 16, in the manner just explained, the outer convolutions of the coiled material and the impervious cup will be held against rotary movement by reason of the friction resulting from the pressure with which the cup is held against the receptacle wall. As soon as this pressure sufficiently diminishes to permit the cup and outer convolutions of the coil to turn, the stopper is readily removable. Figure 6 illustrates the loop 16 of staple B turned a few degrees from the position shown in Figure 5, prior to removal, to coil the inner convolutions of the coiled material more tightly around loop 16. The stopper body tends to assume its normal size when removed from the receptacle, and hence may be used repeatedly.

In Figures 12 to 14 I have illustrated an effective but extremely simple stopper which comprises a single strip I, of heavy manila paper or the like, which has its ends coiled in the same direction around its intermediate portion indicated at 22. The extremity of the outermost convolution of the coil may be free or may be adhesively secured to itself, as preferred. The coiled strip is received within a cup J of metal foil, paraffined or waxed paper or the like, and an impervious disc K is preferably interposed between the

lower end of the strip and the bottom of the cup. At L is illustrated a paper cap or head which may be adhesively secured to cup J or may simply fit snugly thereon, as preferred. Cap or head L is preferably marked with a pair of dots or circles 23-23 which are located above and on opposite sides of the portion 22 of the coiled strip.

The form of stopper shown in Figures 12 to 14 is inserted into a receptacle in the manner previously described, i. e., by direct pressure exerted on the stopper. The stopper is removable by means of a key of the type illustrated in Figure 15. The spaced and pointed legs of the key are thrust through the dots or circles 23 and are forced downwardly into the stopper with the legs of the key lying on opposite sides of the strip portion 22. The stopper is then readily removed by turning the key in a direction which will tend more tightly to coil the inner convolutions of the strip. The cap L may, of course, be provided with any suitable direction indicia, as illustrated.

Having thus described my invention, what I claim as new and desire to secure by Letters Patent of the United States is:

1. A container stopper having an axially inextensible body comprising a coiled strip of material, the body having a normal form adapting it to be forced into a container to effect a fluid tight closure thereof, the strip being adapted thereafter to be coiled more tightly, a member engaging the strip, and a head secured to the member and closely overlying the body, the head being of substantially greater diameter than the body so as to project over the wall of a container opening, the head being adapted, on rotative movement, to coil the strip more tightly, whereby the body will be released from a container, and, on removal, will assume its normal form.

2. A container stopper having an axially inextensible body comprising a coiled strip of material, the body having a normal form adapting it to be forced into a container to effect a fluid-tight closure thereof, the strip being adapted thereafter to be coiled more tightly, a member engaging the strip, a head secured to the member and closely overlying and projecting peripherally beyond the body, the head being adapted, on rotative movement, to coil the strip more tightly, whereby the body will be released from a container and, on removal, will assume its normal form, and an impervious cup of flexible material enclosing the inner end and periphery of the body, the upper margin of the cup lying immediately adjacent the under surface of the head.

3. A container stopper having an axially inextensible body comprising two strips of material coiled together, one of the strips being resilient material, the body having a normal form adapting it to be forced into a

container to effect a fluid-tight closure thereof, the strips being adapted thereafter to be coiled more tightly, a member engaging the strips, and a head secured to the member and closely overlying the body, the head being of substantially greater diameter than the body so as to project over the wall of a container opening, the head being adapted, on rotative movement, to coil the strips more tightly, whereby the body will be released from a container, and, on removal, will assume its formal form.

4. A container stopper having an axially inextensible body comprising two strips of material coiled together, one of the strips being resilient material, the body having a normal form adapting it to be forced into a container to effect a fluid-tight closure thereof, the strips being adapted thereafter to be coiled more tightly, a member engaging the strips, a head secured to the member and closely overlying and projecting peripherally beyond the body, the head being adapted, on rotative movement, to coil the strips more tightly, whereby the body will be released from a container and, on removal, will assume its normal form, and an impervious cup of flexible material enclosing the inner end and periphery of the body, the upper margin of the cup lying immediately adjacent the under surface of the head.

5. A container stopper having an axially inextensible body comprising a coiled strip of material, the body having a normal form adapting it to be forced into a container to effect a fluid-tight closure thereof, the strip being adapted thereafter to be coiled more tightly, a winding loop disposed at the axis of the body embracing the sides and lower edge of the strip intermediate its ends, and a head fixedly secured to the upper end of the loop and closely overlying and projecting peripherally beyond the body, the head being adapted, on rotative movement, to coil the strip more tightly, whereby the body will be released from a container and, on removal, will assume its normal form.

6. A container stopper having an axially inextensible body comprising a coiled strip of material, the body having a normal form adapting it to be forced into a container to effect a fluid-tight closure thereof, the strip being adapted thereafter to be coiled more tightly, a winding loop disposed at the axis of the body embracing the sides and lower edge of the strip intermediate its ends, the legs of the loop being formed to provide shoulders extending radially from the axis of the body across the top thereof, and a head seated on the shoulders and secured to the extremities of the legs at the outer edges of the shoulders, the head closely overlying and projecting peripherally beyond the body, the head being adapted, on rot-

- 52
5. A container stopper having an axially inextensible body comprising two strips of material coiled together, one of the strips being resilient material, the body having a normal form adapting it to be forced into a container to effect a fluid-tight closure thereof, the strip being adapted thereafter to be coiled more tightly, a winding loop disposed at the axis of the body embracing the sides and lower edge of the strip intermediate its ends, the legs of the loop being formed to provide shoulders extending radially from the axis of the body across the top thereof, a head seated on the shoulders and secured to the extremities of the legs at the outer edges of the shoulders, the head closely overlying and projecting peripherally beyond the body, the head being adapted, on rotative movement, to coil the strips more tightly, whereby the body will be released from a container and, on removal, will assume its normal form, and an impervious cup of flexible material enclosing the inner end and periphery of the body, the upper margin of the cup lying immediately adjacent the under surface of the head.
6. A container stopper having an axially inextensible body comprising a coiled strip of material, the body having a normal form adapting it to be forced into a container to effect a fluid-tight closure thereof, the strip being adapted thereafter to be coiled more tightly, a winding loop disposed at the axis of the body embracing the sides and lower edge of the strip intermediate its ends, the legs of the loop being formed to provide shoulders extending radially from the axis of the body across the top thereof, a head seated on the shoulders and secured to the extremities of the legs at the outer edges of the shoulders, the head closely overlying and projecting peripherally beyond the body, the head being adapted, on rotative movement, to coil the strips more tightly, whereby the body will be released from a container and, on removal, will assume its normal form.
7. A container stopper having an axially inextensible body comprising a coiled strip of material, the body having a normal form adapting it to be forced into a container to effect a fluid-tight closure thereof, the strip being adapted thereafter to be coiled more tightly, a winding loop disposed at the axis of the body embracing the sides and lower edge of the strip intermediate its ends, the legs of the loop being formed to provide shoulders extending radially from the axis of the body across the top thereof, a head seated on the shoulders and secured to the extremities of the legs at the outer edges of the shoulders, the head closely overlying and projecting peripherally beyond the body, the head being adapted, on rotative movement, to coil the strips more tightly, whereby the body will be released from a container and, on removal, will assume its normal form.
8. A container stopper having an axially inextensible body comprising two strips of material coiled together, one of the strips being resilient material, the body having a normal form adapting it to be forced into a container to effect a fluid-tight closure thereof, the strips being adapted thereafter to be coiled more tightly, a winding loop disposed at the axis of the body embracing the sides and lower edge of the strips intermediate their ends, the legs of the loop being formed to provide shoulders extending radially from the axis of the body across the top thereof, and a head seated on the shoulders and secured to the extremities of the legs at the outer edges of the shoulders, the head closely overlying and projecting peripherally beyond the body, the head being adapted, on rotative movement, to coil the strips more tightly, whereby the body will be released from a container and, on removal, will assume its normal form.

In witness whereof, I hereunto subscribe my name this 10th day of August, 1921.

HERBERT J. BRAGDON.
